UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

HANGER FOR WEARING APPAREL

Application filed June 6, 1929. Serial No. 368,906.

This invention relates to hangers for wearing apparel, being designed more especially although not exclusively, as a closet hanger to support such articles as hats, coats and neckwear in convenient and readily accessible position.

The main object of the invention is to provide a simple, inexpensive, and very compact apparel hanger, which may be readily mounted on a molding strip of the wall, or on a horizontal panel frame member of a door, and which will serve to support a plurality of articles of wearing apparel within a comparatively compact space.

Another object of the invention is to provide an improved hat holder well adapted to support both men's hats and women's hats in a fashion which will avoid any danger of puncturing or deforming the material of the hat through contact with either the holder or the wall of the room or closet.

Still other objects and attendant advantages of the invention will be apparent to persons familiar with articles of this character from the following detailed description, taken in connection with the accompanying drawings, in which I have illustrated a simple and practical embodiment of the invention well adapted to serve the stated purposes and objects thereof, and wherein—

Fig. 1 is a front elevation of the hanger showing the same mounted on a molding strip.

Fig. 2 is a side elevation, viewed from the right of Fig. 1.

Fig. 3 is a top plan view of Fig. 1.

Fig. 4 is a sectional detail on the line 4—4 of Fig. 2 through the pivot joint of the adjustable hat holder.

Fig. 5 is a sectional detail on the line 5—5 of Fig. 3, showing the pivot joint of the hat holder in edge elevation.

Fig. 6 is a horizontal section on the line 6—6 of Fig. 1, looking downwardly.

Referring to the drawings, 10 designates as

an entirety an upright metal bar or post which, for the sake of combined strength and lightness, is preferably of a wide V-shape in cross section, as shown in Figs. 3 and 6. The lower portion 11 of this post is preferably 50 slightly offset forwardly, as shown in Fig. 2, and is apertured to receive fastening screws 12 by which it is mounted on a molding strip or other suitable support indicated at 13. The upper portion 14 of the post 10 is forwardly offset, as clearly shown in Fig. 2, and its extreme upper portion 15 is warped and flattened into a vertical plane, and apertured to receive a pivot bolt 16. Mounted on the pivot bolt 16 is an angularly adjustable 60 hat holder. In the preferred structure herein illustrated, this hat holder takes the form of a sheet metal disc 17, portions of which are excised and bent downwardly and inwardly as shown in Fig. 5 to form a pair of 65 parallel hinge lugs 18 that straddle the flattened upper end portion 15 of the post, and are apertured to receive the pivot bolt 16. The relatively large round hat holder 17 provides a board support for a hat, and it is 70 preferably provided with front and rear depending flanges or skirts 17'. When used to support a lady's hat, it is preferably placed in the horizontal position indicated by full lines in Figs. 1, 2 and 3, the forward off- 75 setting of the holder enabling the crown of a lady's hat to rest on the holder with ample room in rear thereof for the brim, without the latter being crowded against the wall. When used as a support for a man's hat the 80 holder is preferably tipped downwardly and forwardly, as shown by dotted lines in Fig. 2, the crown of the hat hanging easily from the round periphery of the holder. The tilting movement of the holder 17 may be 85 limited in both directions by means of an offset stop lug 19, best shown in Fig. 5, formed on the lower forward portion of the member 15.

By reference to Fig. 2, it will be observed 90

that the pivot joint between the hat holder and the post lies above the plane of the lower edges of the flanges 17', so that, by leaving the disc 17 unflanged on opposite sides of the pivot lugs or ears 18, access is readily had to the pivot bolt for assembling and adjusting purposes.

- 5 In the complete and preferred form of the article herein illustrated, the lower portion of the post is equipped with a pair of clothes hooks 20 secured to and projecting forwardly of the lower portion 11 of the post as by pins or rivets 21; and the intermediate portion of the post is provided with a forwardly projecting arm 22 constituting a scarf holder or rack, the forward end portion of the arm being flattened and curled to form a round knob 23 serving as a stop to prevent the scarf from slipping off the end of the arm.
- 10 20 The arm 22 is formed with a downwardly bent shank portion 22' shaped to fit the outer surface of the post 10, and secured to the latter by a rivet 24.

As above stated, the described hanger has primarily been designed to serve as a clothes closet hanger, and when so used may be mounted on a horizontal molding strip in a closet, which carries the ordinary clothes hooks, or on a horizontal panel frame bar on the inner side of the closet door. The specific structure illustrated and described lends itself well to simplicity and economy of manufacture; but many of the structural details may be modified or varied without involving any departure from the substance of the invention as defined in the appended claims.

I claim:

1. In a device of the class described, a post adapted to be secured to a wall or the like and having an outwardly extending upper portion, said post being distorted so as to be stiffened throughout the major portion of its length and the upper extremity thereof lying in a substantially vertical plane, a hat supporting member comprising a relatively stiff sheet member, said sheet member having an integral portion depending substantially centrally thereof, and means pivotally connecting said depending portion to the upper portion of said post.
- 40 45 50 55 60 65 70 75 80 85 90 95 100 105 110 115 120 125 130
2. In a device of the class described, a post adapted to be secured to a wall or the like and having an outwardly projecting upper portion, said post being formed of sheet metal and longitudinally bent so as to be stiffened throughout the major portion of its length, the upper extremity thereof being twisted so as to lie in a substantially vertical plane, a hat supporting member formed of relatively stiff sheet material and having a pair of integral ears stamped from the body portion thereof and bent downwardly therefrom so as to embrace the upper portion of said post, and a pintle extending through said post and said

ears so as pivotally to connect said hat supporting member to said post.

3. In a device of the class described, a hat supporting member formed of stiff sheet material and comprising a substantially flat disc having opposed segmental depending flanges, and an integral ear depending from said disc apertured to receive a pivot bolt, the aperture of said ear being above the plane of the lower edges of said flanges, and the periphery of said disc being unflanged on opposite sides of said ear to permit easy access to said pivot bolt.

JAMES H. BOYE.
